APPARATUS FOR SELF-ADMINISTRATION
OF ANESTHETICS

Justin G. Sholes, Cleveland, and Oris J. Smith,
Cleveland Heights, Ohio, assignors to The Ohio
Chemical and Manufacturing Company, Cleve-
land, Ohio, a corporation of Ohio

Application December 10, 1937, Serial No. 179,060

5 Claims. (Cl. 128—203)

This invention relates to apparatus for the administration of an anesthetic gas or gases in which the patient himself controls the supply of gas to his lungs for the purpose of producing analgesia, or, at most, no more than shallow anesthesia from which the patient speedily regains consciousness. It is to be understood that the terms "gas" and "anesthetic" are used herein to include a vapor as well as a gas strictly so called, and also a vapor or vapors, and mixtures wholly gaseous or vaporous, or gaseous and vaporous.

The chief object of the invention is to provide an apparatus in which the valve controlling the flow of gas will be automatically closed whenever the patient ceases to operate the control mechanism or device, so that if he should become unconscious the valve will close and thus cut off the supply of gas regardless of the position of the control mechanism when he ceases to actuate it. Another object of the invention is to provide an improved apparatus of simple character, unfailing in operation, and capable of being manufactured at low cost. A further object is to provide an apparatus in which, under the control of the physician, dentist, or other attendant, another gas, say one of greater analgesic or anesthetic potency, or a resuscitating or a therapeutic gas, for example oxygen, can be administered when the attendant deems it desirable. Still another object is to provide an apparatus which is especially adapted for the administration of nitrous oxide or other anesthetic gas in dentistry and in surgical operations of a minor nature, as for example lancing a boil, setting a broken bone, or reducing a dislocation. To these and other ends the invention comprises the novel features of construction and combinations of elements hereinafter described.

Of the various constructions in which the invention can be embodied we have selected for illustration and specific description herein the one which is at the present time considered as exhibiting the invention in its most effective and advantageous form.

Referring now to the accompanying drawings:

Fig. 1 is a side view of the complete apparatus, the contractile and expandible rubber bulb, which the patient alternately compresses and releases to control the supply of gas, shown partly in section.

Fig. 2 is a side view from the left of Fig. 1 and on a larger scale, the control-valve mechanism being shown in longitudinal section with the valve open.

Fig. 3 is a plan view of the head, with the tubular cross bar, or gas cylinder support, in longitudinal section to show the connection of one cylinder to the pressure regulator or pressure-

reducing valve through which the gas is supplied to the patient-controlled valve mechanism, and the connection of the other cylinder to the doctor's valve.

Fig. 4 is a detail view, in longitudinal section, on line 4—4 of Fig. 2, of the patient-controlled valve mechanism, showing the valve in closed position.

Fig. 5 is a sectional view of the reservoir portion of the apparatus provided for the admixture of air with the gas and for equalizing or stabilizing the flow of the thus mixed fluid to the mask.

Fig. 6 is a detail section of the mask designed for use in dentistry.

The apparatus illustrated comprises a supporting standard 16 mounted on casters and carrying at the top a tubular crosshead 11 having yokes of conventional type 12, 13 to hold the bottles or cylinders 14, 15. Cylinder 15 is connected through one part of the crosshead to the pressure reducing valve 16 which is equipped with a high-pressure gauge 17 to indicate the pressure in the cylinder when valve 12 is opened by turning the handle 19, and a low-pressure gauge 20 to indicate the pressure at the reducing-valve outlet, as determined by the adjustment of the valve by the handle 21. The apparatus may also have further control means, to be operated or set by the doctor, as for example a needle valve 22 for controlling the rate of flow of the gas. This valve may have an "off" position, from which the valve is progressively opened to "light," "medium," and "heavy" positions, which may be marked on the dial to signify the extent of the analgesia to be produced. Thus if it is observed that the patient operates the patient-controlled mechanism rapidly the doctor may set the valve 22 at "light," to minimize the possibility of the patient getting enough gas to cause him to lose consciousness; and conversely the valve may be set at "medium" or "heavy" as the doctor may deem necessary to insure that enough gas will be delivered for effective analgesia in the case of a patient who is observed to operate the patient-controlled valve mechanism slowly.

The cylinder 14, which may, for instance, contain oxygen, is connected by the other part of the tubular cross-head 11 to valve 23 (operated by the doctor) and thence by a flexible tube 24 to the patient as hereinafter described.

The gas from valve 22 passes to the patient-control mechanism 25, which latter is connected by a flexible tube 26 to one arm of a Y or T fitting 27 in the end of a flexible tube 28; tube 24, from doctor's valve 23, being attached to the other arm of the Y. Tube 28 leads to what we may term a reservoir or a mixing chamber since it serves to admit air and mix it with the gas and also serves

to store more or less of the resulting mixture, usually under light pressure. This reservoir, connected to the flexible tube 28, comprises a corrugated non-collapsible tube 29, provided with 5 a plurality of ports 30 for outflow of gas or air and gas to the light expandible balloon 31 surrounding the tube. At the inlet end of the tube is a check-valve comprising a thin flexible rubber disk 32 to permit inflow of air but prevent 10 outflow from the tube, and at the other end is a similar valve 33 arranged to permit outflow but prevent inflow. The outlet end of the mixing reservoir is detachably connected by a pair of flexible rubber tubes 34 to a mask 35, which in 15 the form illustrated is of a shape and size to fit over the patient's nose, leaving the mouth free to be opened at will. At the reservoir the tubes are connected to the tube 29 by means of a bushing 36 releasably but firmly fitting the sleeve 37, 20 and at the mask the tubes are detachably connected to the tubular inlets 38 by means of suitable fittings 39. The mask 35 is equipped with an exhaling check valve 40. It will be seen that the check valve 40 prevents inhalation except 25 through valve 33 and that the latter prevents exhalation into the reservoir.

The patient-controlled valve mechanism 25, shown in Figs. 1, 2, and 4, comprises a casing 45 conveniently made in cylindrical form, and attached to the valve 22. The casing is divided by an interior partition or septum 46 into a gas chamber 47 and a valve-operating chamber 48. Gas from the pressure-reducing valve 16 and doctor's valve 22 enters the gas chamber 47 30 through a passage 49 formed in the partition 46 and terminating in a valve seat 50 to cooperate with a valve member 51 which is freely movable in the chamber but is urged into closed position on the valve seat by an expansible coil spring 52 35 tensioned by compression between the valve and the cap 53 screw-threaded on the casing. The valve member may have a resilient insert 54 to bear on the edge of the valve seat to insure hermetic sealing of the gas passage 49 when the 40 valve is closed. The gas chamber is provided with an outlet nipple 55 to which the tube 26, described above, is detachably fitted.

In the valve-operating chamber 48 is a valve-actuating member in the form of a plate 56 45 equipped with pins or rods 57 guided smoothly and easily in openings in the partition so that when the member is advanced (i. e., toward the right in Fig. 4) the pins will push the valve member 51 off the valve seat 50 against the tension 50 of the valve-closing spring 52 and thus permit gas to flow from the gas inlet passage to the chamber and thence through nipple 55 to tube 26. The member or plate 56 is itself moved rightwardly by air pressure acting through the instrumentality of an expansible and collapsible means 55 which is preferably a soft elastic rubber disk 58 having a peripheral flange 59 extending into a circumferential groove in the end of the valve casing. A cap 60, screw-threaded on the casing, 60 clamps the diaphragm on the edge of the casing to seal the chamber against the escape of gas entering the same along the pins 57. The cap is provided with a nipple 61 for connection with a flexible rubber tube 62 at the other end of which 65 is a rubber bulb 63. At the outer end of the bulb a check valve 64 is provided to prevent escape of air when the bulb is compressed but permit free inflow of air as the bulb expands. At the other end of the bulb is a check valve 65 70 permitting free flow air to the tube 62 and thence

to the valve-operating chamber 48 when the bulb is compressed but preventing back-flow from the chamber to the bulb when the latter is released. The cap 60 is also provided with an air-vent for escape of air from behind (the left 5 of) the diaphragm. This vent is preferably in the form of a short tube 66 having a transverse passage 67 close to the surface of the cap 60 to minimize accidental stoppage of the vent and make intentional stoppage by the fingers practically if not wholly impossible. 10

To insure firm and hermetic seating of valve member 51 on the seat 50 we prefer to have slight lost motion between the valve-opening means, in the present instance the plate 56 and pins 57, 15 so that the former can seat itself even if the plate and pins are in slightly advanced position. The construction illustrated, in which the pins are not attached to the valve member, is also advantageous as facilitating assembly of the parts and 20 permitting parts in one compartment or chamber to be removed without disturbing the parts in the other.

The operation of the apparatus is as follows: The pressure-reducing valve or regulator 16 is 25 opened by the doctor by means of handle 21, then valve 18, on the cylinder containing the anesthetic, is opened, causing the cylinder pressure to be indicated on gauge 17, after which the regulator or pressure-reducing valve is adjusted 30 by the doctor, while compressing and releasing bulb 63 energetically, until the needle on gauge 20 swings to a suitable low point, which, in the case of nitrous oxide, may be about 5 pounds per square inch. The tubes 34 are then passed over 35 the patient's head and the mask is fitted over his nose, after which the sliding clamp 70, Fig. 1, is pushed up toward the back of the head to a point at which the soft flexible tubes hold the mask closely but comfortably in place. Desiring to 40 prevent or relieve any pain that he may expect or feel, the patient compresses and releases the bulb repeatedly. Compression forces air from the bulb and against the diaphragm 58, thus expanding the same against the plate 56 and moving 45 the valve member 51 off the seat 50. Gas then flows through tubes 26 and 28 to the reservoir 29-31, when a mixture of gas and air is drawn into the patient's lungs as he inhales. The patient is instructed to compress and release the 50 bulb vigorously and rapidly at first until he experiences loss of sensation, and then to compress the bulb only occasionally as he feels the need for more gas. At each compression, air leaks out from behind the diaphragm 58 through 55 the small air vent 66, but if re-compression follows release promptly the valve can be held open, the outflow of air through vent 66 being too slow to permit the valve to close before the next 60 impulse from the bulb. However, if the patient despite the doctor's instructions works the bulb too rapidly, or because of unexpected sensitivity to the gas, should become unconscious, the resulting cessation of the "pumping" action will 65 permit the valve to close, thus cutting off further flow of gas to the tube 26; and it will be seen that this closing of the valve occurs no matter at what stage of compression or expansion the patient may hold the bulb when he loses consciousness. Also, the doctor or attendant can at any time open valve 23 and allow oxygen to flow to the patient from cylinder 14. 70

It is to be understood that the invention is not limited to the specific construction herein illus- 75

trated and described but can be embodied in other forms without departure from its spirit.
